UNITED STATES PATENT OFFICE.

WILLIAM PERTRAM, OF KIRKWOOD, MISSOURI.

AUTOMATIC FOOTSTOOL.

Application filed February 26, 1926. Serial No. 90,917.

The object of my device is to make an automatic foot stool of the type that is used in shoe stores, on which the shoe salesman sits and upon which the customer places his 5 foot. A further object is to make an automatic foot stool that can be made to remain in a stationary position and one that can be rolled about on the floor on which it is positioned. A further object is to make an 10 automatic foot stool that can be moved around by the salesman when he is sitting on it, but which will be locked to the floor when the salesman leaves his seat. With the conventional foot stool used in shoe 15 stores, when the salesman leaves his seat on the stool, the pressure of the foot of the customer pushes the stool away from the customer, thereby causing him to be forced to put his foot on the floor instead of on the 20 stool. By my device this is obviated because if the salesman for any reason must arise from his seat on the stool, the pressure of the foot of the customer cannot push the stool away because the stool is locked to 25 the floor. Furthermore, this unnecessary movement of the stool on the floor or carpet has a tendency to wear out the carpet and scratch and mar the floor surface. With my stool there is no unnecessary movement. 30 In order to prevent the scratching or marring of the floor and its covering, the wheels of my stool are rubber tired. A further object of my stool is to make the locking arrangement between the stool and the floor 35 inoperative so that the stool may be moved around at will, as is the conventional stool on rollers, as when the floor is cleaned, etc. A still further object is to make the locking 40 device between the stool and the floor when the salesman arises from the stool automatic. A still further object is to supply the stool with a tool box for the reception of a shoe horn and shoe buttoner, etc.

With these and other objects in view, my 45 invention has relation to certain novel features of construction and arrangement of parts, as will be hereinafter more fully described, pointed out in the claim, and illustrated in the drawings, in which,

50 Fig. 1 is a side elevation of my device partly in section, showing the locking device in unlocked or inoperative position.

Fig. 2 is a fragmental longitudinal sectional elevation of my device showing the 55 locking means in operative position and in

locked position, that is, in engagement with the floor.

Fig. 3 is a rear elevation of my device broken away as to show a portion of the stool in section.

Numeral 4 designates the stool proper, the rear part of which is used for the seat for the shoe salesman and the front part of which is used for the support of the customer's foot. The stool proper is formed of 60 two side members 5 of the shape best shown in Fig. 1 and the front and rear members 6 and 7 respectively. The side and front and rear members are secured together by nailing or other conventional means. The lower 65 portions of the side members 5 form the feet 8, of which there are four. By means of the axles 9, the rubber tired wheels 10 are rotatively mounted on the feet 8. The front part of the stool is inclined as best shown in 70 Fig. 1. The inclined member 11 is secured to the side members 5 and the front member 6, as best shown in Fig. 1. This inclined member 11 is the customer's foot support. Numeral 12 designates a stop strip secured 75 to the outer end of the inclined member 11 in order to prevent the customer's foot from slipping off the inclined member 11. The pocket 13, which is preferably made of metal and which is secured at one end to the under- 80 side of the inclined member 11 and at the other end to the top 14, forms the tool box. The ends of the pocket 13 are secured to the side members 5. The top 14 is rectangular 85 in shape and is secured to the side members 90 5 and the rear member 7. The device thus far described forms a foot stool that may be rolled about as is the conventional foot stool. All of the stool thus far described, with the exception of the wheels and axles, and the 95 pocket are preferably made of wood, or similar material.

Numeral 15 designates a rectangular cap that fits over the top 14. This cap is made of the top 16 and the sides 17. The sides 100 17 are of sufficient height so as to extend down the side members 5 and the rear member 7 a short distance when the top 16 is held in spaced relationship with the top 14. The stems 18, of which there are four, are 105 secured to the underside of the top 16, near the corners, and protrude through openings 19 in the top 14, as shown in the drawing. Numeral 20 designates U-shaped members, 110 of which there are four, having holes formed

into the parallel portions of such size as to permit the stems 18 to pass therethrough. In order to accomplish this, these holes must be in alinement. These U-shaped members 5 are secured to the underside of the top 14 immediately beneath the openings 19 so that the stems 18 can freely be moved in the holes in the parallel portions of the U-shaped members. These U-shaped members may 10 be secured in any conventional manner, preferably to the side members 5 by means of screws or bolts. Numerals 21 designate coiled springs which are positioned around the stems 18 between the parallel portions 15 of the U-shaped members 20. The purpose of the coiled springs 21 is to normally hold the top 16 in spaced relationship with the top 14. This is done by making the coiled springs 21 of sufficient length to occupy the 20 entire space between the parallel portions of the U-shaped members 20 and by securing split pins 22 through the stems 18, immediately beneath the upper parallel portions of the U-shaped members 20. It will be seen 25 that when the top 16 is pressed downwardly that the coiled springs 21 are compressed on the lower parallel portions of the U-shaped members 20. When the pressure on the top plate 16 is released, the coiled springs 30 21 return the top 16 to its normal position, shown in the drawings. It will be seen that when the shoe salesman sits on the top 16 that his weight will push the top 16 down against the coils of the coiled springs 21, 35 provided that the coiled springs are of such design as to permit their compression by the imposition of the weight of an average individual on the top 16.

Numeral 23 designates a rod secured to 40 the underside of the top 16 and passing through a hole in the top 14 and having the bifurcated end 24.

Numeral 25 designates a locking frame having the side members 26 and the horizontal members 27 securing the side members 26 together. Numerals 28 designate journal blocks secured to the side members 5 on the inside, as shown in the drawing.

Numeral 29 designates a rod passing 45 through holes near the top of the side members 26 and having its ends protrude into holes in the journal blocks 28. It will be seen that by this means, the locking frame 25 is rotatively secured to the side members 5.

At the bottom of the side members 26 is secured the clutch 30 which has the depression 31 formed therein, forming thereby the sharp edge 32. The clutch 30 is positioned 55 at an angle relative the sides of the locking frame 25, as best shown in Figs. 1 and 2. Numeral 33 designates a wiper which is secured to the clutch 30 and is preferably made of rubber or other resilient material, and the free end extends considerably 60 beyond the end of the clutch 30. Numeral 34

designates a U-shaped spring, in the one end of which is an eye, which is rotatively secured to the rod 23 by having the end extended between the forks of the bifurcated end, and having a pin 35 pass through the eye of the U-shaped spring 34. The other end of the U-shaped spring 34 is secured to the upper horizontal member 27 of the locking frame 25. The U-shaped member is of such shape and size and is so positioned that 70 in the normal position of the top 16 the locking frame 25 is substantially in a vertical position. The side members 26 of the locking frame 25 are of such length that when the top 16 is in its normal position that the 75 wiper 33 will be pressed against the floor 36 on which the stool rests. The resilient material of which the wiper 33 is made, compresses a portion of it in the depression 31 and thereby presents the sharp edge 32 80 with the wiper 33 pressed against the floor and thereby secures a firm and positive engagement between the clutch and the floor. In this position the foot stool cannot be 85 rolled or moved over the floor. In order to move the stool over the floor by rolling, it is necessary that the clutch 30 be disengaged from the floor. This disengaging is accomplished by the shoe salesman sitting on the top 16, thereby compressing the rod 23 and 90 pushing downwardly on the one arm of the U-shaped spring 34, and thereby rotating or oscillating the locking frame 25 in an anti-clock wise direction, thereby slightly lifting the clutch 30 from the floor, but thereby disengaging it from the floor, and thereby permitting the shoe salesman to move the stool around by moving his feet on the floor as he would in walking. The shoe salesman, of 95 course, straddles the foot stool, one leg being suspended from each side of the stool. When the shoe salesman gets off of the top 16, the coiled springs 21 bring the top 16 back to its normal position and thereby bring the clutch 30 in the position shown in 100 Fig. 2, and thereby again lock the stool to the floor.

In order to make the clutch 30 inoperative when the operator sits on the stool, or when he does not sit on the stool, it is necessary 105 to secure the clutch 30 out of engagement with the floor and so that it remains out of engagement when the top 16 is in normal position. In order to lock the locking frame 25 and hence the clutch 30, out of engagement with the floor, an angle iron 37 is secured to the lower horizontal member 27 of the locking frame 25, the free end extending through an opening in the rear member 7. The angle iron 37 has a notch 110 38 formed in its outer free end. Numeral 39 designates an arm rotatively secured to the rear member 7 by means of the pin 40. The arm 39 is so positioned relative the 115 opening in the rear member 7 that when 120 125 130

the notch 38 of the angle iron 37 extends therethrough, that the arm 39 may be rotated into the notch 38, thereby preventing the release of the angle iron 37 and thereby holding the locking frame 25 in the position shown in Fig. 1, that is to say, out of engagement with the floor 36. In order to make the clutch 30 operative, it is only necessary to rotate the arm 39 in a reverse direction, thereby disengaging the arm from the notch 38 and permitting the angle iron 37 to pass back through the opening in the rear member 7.

What I claim and mean to secure by Letters Patent is,

In combination with an automatic stool,

a cap mounted thereon for vertical reciprocation and normally held in spaced relationship with the top of the stool, a locking frame rotatively secured in said tool, a 20 rod secured to said cap and extending through the top of said stool, a spring connecting said locking frame and said rod, a clutch secured to said locking frame so that when a weight is placed on the top of said stool, said clutch will be raised above the floor on which the stool is positioned, and when the weight is removed, the clutch will become engaged with the floor. 25

In testimony whereof I affix my signature.

WILLIAM PERTRAM.
